UNITED STATES PATENT OFFICE.

JUAN C. MONTERO, OF WASHINGTON, DISTRICT OF COLUMBIA.

PROJECTILE.

1,316,917.

Specification of Letters Patent. Patented Sept. 23, 1919.

Application filed April 6, 1918. Serial No. 227,010.

To all whom it may concern:

Be it known that I, JUAN C. MONTERO, a citizen of the Philippine Islands, and a resident of Washington, in the District of Columbia, have invented a certain new and useful Improvement in Projectiles, of which the following is a specification.

My present invention relates to projectiles, and more particularly to a device of 10 this character adapted to be used in naval guns or in coast defense ordnance.

The principal object of my invention is to provide a projectile which can be used for long distance firing or for close range work, 15 and which will not ricochet upon striking the water when fired at a low angle or at a mark close at hand.

A further object is to so construct the projectile that it may be fitted with a contact 20 head, and which due to its construction will carry true to its mark and will strike to explode below the water line; or, which may have a time fuse fitted in conjunction therewith and may then be used effectively as a 25 defense against torpedoes by being properly timed and then fired to dive and carry adjacent the torpedo, the timing mechanism of course being set so that the explosion will occur when the projectile is in a proximate 30 position.

Further objects of my invention will appear in the following description, taken in conjunction with the accompanying drawing, forming a part of this specification, and 35 in which drawing:

Figure 1 is a view in elevation of a projectile constructed after the manner of my invention.

Fig. 2 is a view taken somewhat after the 40 manner of Fig. 1 and with parts illustrated in vertical section to better disclose the construction and assembly of the elements of the projectile.

Fig. 3 is a cross sectional view through 45 the inner member of the projectile, taken substantially on the line $x-x$ of Fig. 2.

Fig. 4 is a sectional view through the outer

member of the projectile, and also taken on the line $x-x$ of Fig. 2.

In the drawing, where similar characters 50 refer to similar parts throughout the views, A designates an outer member of tubular form which is closed at one end, and which might be turned out of a forging, or made up in any other desired manner, while B 55 designates an inner member made of cylindrical contour and adapted to be fitted within the tubular member.

As has been stated, the outer member A is made of substantially tubular form by 60 having a bore 1 provided therein and extending axially, the rear end being closed as indicated at 2, and the forward end being reamed around the bore as at 3, to provide a cup. The inner member B is in its main 65 line of substantially cylindrical form, and the forward end is shaped to provide the spiral vanes 4, which are given a pitch to conform substantially to the rifling of the gun from which the projectile is to be fired, 70 it of course being understood that these vanes will be turned so that as the projectile revolves in its flight a boring in action is accomplished, and as is better shown in Fig. 3, the vanes are made somewhat sharp 75 on their forward edges, and might even be undercut should this be deemed desirable. The inner end of the member B is left without cutting and is made of the full diameter, and is then bored to provide an explosive 80 chamber 5, a firing cap 6, which is here shown as of the contact or percussion type being provided to fire this charge at the proper time and to burst the projectile. The passages between the vanes 4 terminate in a 85 sloping shoulder 7, and the outer member A is cut through at its sides to provide passages 8 which communicate with the spaces between the vanes 4 when the two parts of the projectile are properly assembled, it of 90 course being understood that the rib portions or spokes 9 between the passages or openings 8 are given the same curve or twist as the vanes 4 so that fluid passing between

the vanes will flow in a gradual stream and without interruption through these passages 8.

The use of the projectile will be somewhat as follows:

Assuming that the projectile is to be used in the destruction of ships, as a defense against submarines, or in some other like connection where a relatively large bulk is presented below the water line, the projectile will be fired from a gun in the usual manner, aim however being taken so that in its flight the projectile will strike the water somewhat short of its mark. As the projectile is whirling in such a direction that the vanes 4 are boring through the air caught by the cup 3, this whirling movement is maintained, and when the projectile strikes the water it will submerge and carry in a straight line and a true path due to this whirling force owing to the fact that the water is caught within the cup 3, and also through the boring-in force accomplished by the vanes 4. As the pressure of the water within the cup 3 will be substantially equalized, owing to the fact that an even number of vanes is employed as shown in Fig. 3, and the water will pass in equalized streams back through between the vanes 4 and out of the openings 8, at approximately the center of equilibrium lengthwise of the projectile, the projectile will be balanced in its travel and will carry without deviating from the path of travel followed previous to submersion. In this use, the projectile will carry true to the mark and through contact of the heads 6, with a vessel hull, or other solid objects the projectile will be exploded. Where the projectile is to be used as a defense against torpedoes, it will be fitted with a time fuse, and this fuse will be set, previous to firing, so that the projectile will strike the water and submerge adjacent the torpedo and will then be fired when in proximity thereto.

Since the modern torpedo may be set off or fired by the inertia of a small steel hammer or striker, due to the least shock, ahead or lateral, projectiles constructed according to my invention may be fired in the general path of the torpedo, observing its wake and when exploded the concussion will render the torpedo ineffective as a destruction agent by setting it off prior to its reaching the mark. The projectile may also be effectively used to clear the path of the vessel or vessels of floating mines of the types which are destroyed by rocking and the like. The gun crew may point the guns forwardly or according to the path to be taken by the vessel and use projectiles constructed according to my invention to agitate the water, below its surface, causing such mines to detonate

before the vessel is in such proximity thereto to do any damage.

Changes in details may be made without departing from the spirit or scope of my invention; but,

I claim:

1. A projectile including an outer member and an inner member having longitudinally extending spiral vanes thereon, said outer member provided with a circumferential cavity formed at its forward end, and surrounding said vanes and leading inwardly, constituting means to guard against a ricochet action as the projectile strikes a water surface when fired at a low angle.

2. A projectile including an outer member of substantially tubular form closed at one end and having openings through the sides thereof intermediate its ends, an inner member shaped to provide a plurality of spiral vanes forming spiral passageways in the inner member leading to said openings, the forward end of said outer member having a circumferential cutting edge formed thereon to guard against ricochet action as the projectile strikes a water surface when fired at a low angle.

3. A projectile comprising an outer and an inner member, said outer member having a cup formed at the forward end thereof and being provided with passages through the side thereof spaced rearwardly from the cup, said inner member having vanes thereon extending from the forward end of the inner member to a point opposite the side passages, the vanes providing therebetween passages formed to establish communication from the cup to the side opening passages of the outer member.

4. A projectile comprising with an outer member bored longitudinally and reamed at the outer end of the bore to provide a cup, said outer member having passages leading at the sides thereof from the central bore, an inner member of cylindrical form to be fitted and held within the bore of the outer member provided at its forward end with vanes between which passages are formed to establish communication from the cup of the outer member to the side opening passages thereof.

5. A projectile including with an outer member of substantially tubular form closed at one end and reamed out at the remaining end to provide a cup form, said member having openings through the sides thereof in the middle portion, an inner member of substantially cylindrical form hollowed out at its inner end to provide an explosive receiving chamber and made pointed at its outer end at which point a firing cap is applied, said inner member being shaped to provide vanes spirally disposed thereon to

substantially follow the line of the rifling of the gun from which the projectile is to be fired and having spaced therebetween leading to the openings through the outer 5 member.

6. A projectile including an outer member, an inner member projecting beyond the forward end of the outer member, said outer member provided with a circumferential 10 cutting edge at its forward end and sur-

rounding said inner member to guard against the ricochet action as the projectile strikes the water surface when fired at a low angle.

7. A projectile having a cup at its forward end and vanes leading longitudinally and rearwardly from the cup and terminating in flaring passages at approximately the center of equilibrium of the projectile. 15

JUAN C. MONTERO.
